DESIGN FOR A LENS FOR A HEADLIGHT OR THE LIKE

Albert R. Stahl, Somerset County, Pa.

Application March 15, 1934, Serial No. 51,066

Term of patent 14 years

To all whom it may concern:

Be it known that I, ALBERT R. STAHL, a citizen of the United States, residing in Somerset County, State of Pennsylvania, have invented a new, original, and ornamental Design for a Lens for a Headlight or the Like, of which the following is a specification, reference being had to the accompanying drawing, forming part thereof.

Figure 1 is a view in front elevation of a lens embodying the design;

Figure 2 is a view in rear elevation of the lens; and

Figure 3 is a view in side elevation of the lens.

I claim:—

The ornamental design for a lens for a headlight or the like, as shown.

ALBERT R. STAHL.
